UNITED STATES PATENT OFFICE.

RALPH H. CHILTON, OF TOLEDO, OHIO, ASSIGNOR TO INDUSTRIAL RESEARCH CORPORATION, OF TOLEDO, OHIO, A CORPORATION OF DELAWARE.

GAS-ENGINE STARTER.

Application filed November 16, 1920. Serial No. 424,451.

This invention relates to starting mechanism for engines, particularly of the type which are normally non-selfstarting such as internal combustion engines.

- 5 The invention contemplates the employment of an automatically meshing and demeshing gear wherein the shock of meshing is absorbed by a compression element, in distinction from a tension element.
- 10 An important object is the provision of a resilient element in the drive connection which has the double function of absorbing variations in load between the driving and driven members, and also preventing injury 15 to the gears through improper meshing.

A further object is the utilization of a spring element which is more freely yieldable and resilient when compressed due to improper meshing than when transmitting 20 power.

Still another object is the provision of a resilient element in a starter drive which is not subject to breakage.

Further objects and objects relating to 25 economies of manufacture and details of construction will definitely appear from the detailed description of the invention.

Various preferred modifications of the invention appear in the accompanying drawings in which:

Figure I is a longitudinal section through the drive mechanism;

Figure II is a transverse section of the device shown in Figure I;

Figure III is a view showing a metallic spring connection;

Figure IV is transverse section of the modification of Figure III;

Figure V is plain sectional view of the 40 mechanism of Figure III;

Figure VI shows a modified type of drive spring;

Figure VII is a modification in longitudinal section wherein the sleeve and pinion 45 both have bearing on the shaft; Figure VIII shows the device of Figure VII with a metallic spring employed.

Figure IX is a modification of the arrangement of Figure VII showing the use 50 of metallic springs.

Referring to Figure I the shaft 10 is extended from any conventional power source such as an electric motor 11 and screw threads 12 are cut thereupon. In meshing 55 engagement with the threads 12 is an in-

ternally threaded sleeve 13 on the outer surface of which ridges 14 are formed extending axially thereupon. These ridges 14 are adapted to be positioned in axial channels or grooves 15 cut on the inner surface of 60 pinion 16. These channels 15 have a width in excess of that of the ridges 14 and in this excess space between the ridges and one wall of the channels is interposed a resilient element 17 consisting of cork, rubber or fabri- 65 cated material.

The channels 15 do not extend completely across the pinion, a portion 18 of the material of the pinion remaining in place at one end of the channels, the other end being 70 open. At the open or outer ends of the channels plates 19 attached to the sleeve by screws 20 serve to block the channels and hold the resilient material in place.

It is evident that with the above described 75 arrangement of parts, the pinion has rotatable and axial movement on the sleeve limited only by the yield of the resilient material in the pinion channels; and since the yielding material has greater dimensions axially 80 than transversely there is greater yield in an axial than in a transverse direction.

In the operation of the device when the motor shaft is rotated in the direction of the arrow in Figure II the sleeve and pinion move 85 as a unit, with very limited rotation, if any, axially along the shaft and into mesh with the engine member. As soon as the sleeve is stopped by the collar 21 it tends to take on the rotary speed of the drive shaft, but since 90 the pinion is restrained by the load it is prevented from acquiring the motor speed until the inertia of the engine is overcome. By means of the yielding element 17 the shock incident to taking up the engine load is 95 largely absorbed and the drive is then yieldingly carried on through the resilient element.

In case the pinion teeth in moving toward the engine gear fail to mesh properly 100 therewith, the teeth abutting each other, the mechanism is injured or made inoperative unless the parts yield sufficiently to allow slight rotation of the pinion subsequent to which proper meshing occurs. It is desirable that this axial yield of the pinion be 105 free and in practice it has been found necessary in related devices to employ separate spring means of greater flexibility than the drive springs. In this mechanism however 110

the greater length of the resilient material in the axial direction gives it relatively greater yield axially so that this one element properly serves both functions.

After starting the engine accelerates rapidly screwing the pinion and sleeve automatically out of mesh with the engine member.

In the modification shown in Figures III 10 and IV a tongue 30 projecting from the sleeve 31 enters a transversely extending groove 32 in the pinion interior and a coiled spring 33 in this groove normally holds the tongue at the rear end of the groove when 15 rotating to start the engine. A resilient element 34 formed of spring metal or yielding fabric and placed between the pinion and sleeve stops 35 serves to retain the pinion against an inner limiting stop 36 on the 20 sleeve 31 in order to allow axial yield when the gear teeth fail to mesh as was indicated with reference to the preferred form of drive.

In Figure V means for eliminating the 25 yielding element 34 is shown. In this arrangement the tongue 37 and groove 38 are placed at an angle with the shaft axis and the coil spring 39 placed so that it normally tends to hold the pinion in inward position. 30 When either the load is taken up or the teeth abut in starting the spring compresses and the pinion slides outwardly and rearwardly.

Figures VII and VIII illustrate a modified form wherein the pinion 40 is positioned directly on this drive shaft instead of the sleeve. As here shown the sleeve 41 is screw threaded to the motor shaft and the pinion 40 secured thereto by means of pins 42 slidably and loosely mounted in holes 44 drilled axially in the sleeve element. The holes 44 have for a greater part of their length a diameter in excess of the pins 42 and in the excess space resulting yielding material 45 is inserted completely surrounding the pins.

In the operation of this modification the drive is from the shaft through the sleeve 41, the pins 42 and pinion 40 to the engine 50 shaft, the drive shock being taken up by the yielding material 45.

In the modification of Figure IX the coil spring 50 is substituted for the yielding material 45 of Figure VII.

55 I claim as my invention:

1. In an engine starter, the combination

of a drive shaft; a sleeve on the shaft having both rotatable and axial movement; a pinion having limited axial and rotatable movement on the sleeve; and a rubber driving connection between the sleeve and pinion, said connection being adapted to hold yieldably the pinion at one limit of its axial movement on the sleeve and forming a driving connection between the sleeve and pinion, and said sleeve having a shorter torque radius than that of the pinion. 60 65

2. In an engine starter, the combination of a drive shaft; a sleeve on the shaft having both rotatable and axial movement; a pinion having limited axial and rotatable movement on the sleeve; and a yielding driving connection between the sleeve and pinion, said yielding connection being adapted to hold the pinion at one limit of its axial 70 and rotatable movement on the sleeve and forming a driving connection between the sleeve and pinion, said yielding connection being contained within and protected by 75 said pinion, and said sleeve having a shorter torque radius than that of the pinion. 80

3. In an engine starter, the combination of a drive shaft; a sleeve on the shaft having both rotatable and axial movement; a pinion having limited axial and rotatable movement on the sleeve; a yielding driving connection between the sleeve and pinion, said yielding connection being adapted to yield more freely in an axial than in a transverse direction and forming a driving connection 90 between the sleeve and pinion, said yielding connection being contained within and protected by said pinion, and said sleeve having a shorter torque radius than that of the pinion. 95

4. In an engine starter, the combination of a drive shaft; a sleeve mounted for axial and rotatable movement on the shaft, said sleeve having axially extending ridges formed thereon; a pinion slidably and rotatably mounted on the sleeve, said pinion having axial channels in its inner surface adapted to receive and engage said sleeve ridges; and a yielding resilient element interposed in said channels and in juxtaposition with said ridges, said resilient element forming both a yielding driving connection between the sleeve and pinion, and a yielding element for permitting relative axial movement of the sleeve and pinion. 100 105 110

In testimony whereof, I affix my signature.
RALPH H. CHILTON.
